OPHTHALMIC MOUNTING

Joseph W. Aspenleiter, Rochester, N. Y., assignor
to Bausch & Lomb Optical Company, Rochester, N. Y., a corporation of New York

Application December 16, 1935, Serial No. 54,560

8 Claims. (Cl. 88—47)

The present invention relates to ophthalmic mountings and more particularly to means for attaching mountings to lenses to provide rimless spectacles.

When an ophthalmic mounting is to be secured to a lens by means of a screw, it is difficult to drill the lens and position the mounting with sufficient accuracy to prevent either a loose connection or one so tight that it strains the lens. Attempts have been made to remedy this difficulty by inserting a leaf spring between the shoe and the edge of the lens but this spring introduced other difficulties. Unless the mounting were set with great accuracy, one side of the spring would be distorted more than the other and this distorted side would tend to turn the shoe and straps about the screw as an axis. In one direction, this turning would tend to loosen the screw while in the other direction it would tend to tighten the screw and strain the lens. Furthermore any slight force exerted on these connections, such as moving the temples when placing the spectacles in a case, would cause a slight movement of the connection about the screw as an axis and would tend either to loosen or to tighten the screw. Either of these latter results is both undesirable and annoying.

One of the objects of the present invention is to provide a lens connection for an ophthalmic mounting, which connection is simple and easy to attach, yet rugged and durable in operation. Another object is to provide a lens connection having a spring shoe and which will not pivot about the attaching screw. A further object is to provide an ophthalmic mounting having a rigid shoe rockably secured to the lens straps. These and other objects and advantages reside in certain novel features of construction, arrangement and combination of parts as will hereinafter be more fully set forth and pointed out in the appended claims.

Referring to the drawing:

Fig. 1 is an elevation of one embodiment of my invention.

Fig. 2 is a horizontal section thereof.

Fig. 3 is an elevation of another embodiment of my invention.

Fig. 4 is a horizontal section of the embodiment shown in Fig. 3.

In the embodiment shown in Figs. 1 and 2, 10 indicates a lens to which an ophthalmic mounting 11 is secured. The mounting 11 has the usual shoe 12 and a leaf spring 13 is secured to the shoe 12 by suitable means, not shown, so that the spring 13 will contact the edge of the lens 10.

A pivot rod or rivet 14 extends through the shoe 12 and two straps 15 and 16 are pivotally mounted on the rod 14 on opposite sides of the shoe 12 for engaging the opposite surfaces of the lens 10 as shown in Fig. 2. The outer ends of the straps 15 and 16 are perforated at 17 and 18 respectively and a screw 19 is threaded into these perforations and extends through a hole 20 in the lens 10 thus securing the lens to the mounting 11.

The shoe 12 and mounting 11 are pivotally connected to the straps 15 and 16 by the rod 14 and any unequal stress in the spring 13 is taken up by pivotal movement about the rod 14 as an axis instead of pivotal movement about the attaching screw 19 as an axis. Strains placed on the mounting 11 are likewise taken up by pivotal movement about the rod 14 and thus the tendency to turn the screw 19 is eliminated. The shoe 12 and mounting 11 are cut away adjacent the rod 14 and are provided with shoulders 21 which cooperate with the straps 15 and 16 to limit the pivotal movement about the rod 14.

In the embodiment shown in Figs. 3 and 4, the ophthalmic mounting 22 has two spaced arms 23 and 24 rigidly connected to the shoe 25. The leaf spring 26 which engages the edge of the lens 10, is secured to the shoe 25 by a rivet 27. The lens straps 28 and 29 are secured together in the form of a U-shaped member which extends over the shoe 25 between the arms 23 and 24 and engages the opposite surfaces of the lens 10. The straps 28 and 29 are perforated at 30 and 31 respectively, and a screw 19, threaded into these perforations, extends through a hole 20 in the lens 10 and secures the straps 28 and 29 and the mounting 22 to the lens 10. It is apparent that the mounting 22 and shoe 25 are thus free to rock about the U-shaped end of the straps 28 and 29.

From the foregoing it will be apparent that I am able to attain the objects of my invention and provide a lens connection for an ophthalmic mounting which connection is simple and easy to attach yet durable and efficient in use. While I have illustrated my lens connection as applied to end pieces only, obviously it could be as well applied to any ophthalmic mounting for rimless spectacles such as a bridge, stud or the like. Also the means for securing the lens straps to the lens is not limited to a screw but any of the so-called screwless connections may be used. Various other modifications can, of course, be made without departing from the spirit of my invention or the scope of the appended claims.

I claim:

1. In a device of the character described, two straps adapted to be rigidly secured respectively on opposite sides of a lens, means connecting said straps beyond the edge of said lens, a shoe rockably secured on said means, a resilient member between said shoe and the edge of said lens, and an ophthalmic mounting rigid with said shoe. 5
2. In a device of the character described, an 10 ophthalmic mounting, a shoe having an aperture therethrough secured to said mounting, a spring secured to said shoe for engaging the edge of a lens, two spaced straps positioned, respectively, on opposite sides of said shoe and adapted to 15 engage the opposite surfaces of a lens, and a member joining said straps and extending through the aperture in said shoe for pivotally connecting said shoe and said straps.
3. In a device of the character described, an 20 ophthalmic mounting, a shoe rigid with said mounting, resilient means secured to said shoe and adapted to engage the edge of a lens, and two straps pivotally connected to said shoe on opposite sides thereof for securing a lens there- 25 between in engagement with said resilient means.
4. In a device of the character described, an 30 ophthalmic mounting, a shoe rigidly fixed thereto, a resilient member secured to said shoe and adapted to engage the edge of a lens, a rod extending through said shoe, and two straps pivotally mounted on said rod, one on each side of said shoe for engagement with the two surfaces of 35 said lens.
5. In a device of the character described, an ophthalmic mounting, a shoe rigidly fixed thereto, a resilient member secured to said shoe and adapted to engage the edge of a lens, a rod extending through said shoe, two straps pivotally mounted on said rod, one on each side of said shoe for engagement with the two surfaces of 5 said lens and means for limiting the relative pivotal movement between said straps and said shoe.
6. In a device of the character described, an 10 ophthalmic mounting, a shoe having an opening therethrough secured to said mounting, a spring secured to said shoe and adapted to engage the edge of a lens, and a U-shaped strap member adapted to extend loosely through said opening 15 and engage the opposite side of a lens.
7. In a device of the character described, two straps adapted to be rigidly secured on opposite 20 sides of a lens, a shoe rockably mounted on and between said straps beyond the edge of said lens, 25 a resilient member between the shoe and the edge of the lens and an ophthalmic mounting rigidly connected to said shoe.
8. A device of the character described comprising two straps rigidly secured on the opposite 25 surfaces of a lens, means connecting said straps beyond the edge of said lens, a shoe connected to said straps for rocking movement about said means, a resilient member between said shoe and the edge of said lens and an ophthalmic mount- 30 ing rigidly secured to said shoe.

JOSEPH W. ASPENLEITER.
